UNITED STATES PATENT OFFICE.

WILLIAM H. TUTTLE, OF DETROIT, MICHIGAN.

NAIL.

SPECIFICATION forming part of Letters Patent No. 496,625, dated May 2, 1893.

Application filed May 12, 1892. Serial No. 492,746. (No model.)

To all whom it may concern:

Be it known that I, WILLIAM H. TUTTLE, a citizen of the United States, residing at Detroit, county of Wayne, State of Michigan, have invented a certain new and useful Improvement in Nails; and I declare the following to be a full, clear, and exact description of the invention, such as will enable others skilled in the art to which it pertains to make and use the invention, reference being had to the accompanying drawings, which form a part of this specification.

This invention relates to nails, and has for its object an improvement in that class of nails which are especially designed to secure and hold together miter-joints or joints formed by placing two pieces of wood together, end to end, either with a straight cross-cut or with a beveled cross-cut. With a straight cross-cut, the two pieces of wood thus joined would lie in the same straight line; with a beveled cross-cut the two pieces of wood thus joined would lie at an angle. The nail may also be used in joining two pieces, which are squared off, and of which one is abutted against the other.

In the drawings: Figure 1, shows the nail in perspective. Fig. 2, shows two strips of wood cut to be united with a miter-joint and 30 shows the nail partially driven into its holding position. Fig. 3, indicates the position occupied by the nail when used to unite two pieces of wood, where the end of one is abutted against the side of the other.

35 A, represents the nail made of sheet metal, having a body part or web *a*, and two upturned flanges *b*, *c*; at the point *D*, of the nail, the web or body-part is wider than it is at the head *e*, and the flanges *b*, *c*, taper gradually from the head to a short distance above the point at *F*, *F* and from *F*, to the extreme point taper down and disappear, so that the web part of the nail is narrower at the head of the nail than at its point, and the two 40 flanges are wider at the head than they are at the point, and narrow slowly from the head to the points *F*, and then narrow rapidly to the extreme points *G*. This nail may be driven without any previous preparation in 45 soft wood, but in hard wood it is usually de-

sirable to cut with the saw a gain or kerf, in the ends of the pieces to be joined, the depth of cut being about equal in each piece to one-half the width of the wide or point end of the nail, and if the material be very thin, 55 it may sometimes be desirable, to cut with a drill or other similar implement, a passage-way in each of the parts *P*, *P'*, for the flanges *b*, *c*, but usually the pieces to be united will have strength sufficient to withstand the 60 slight strain caused when the nail is forced into its position. The two pieces to be united are placed in the position they are to occupy with respect to one another, and the nail is driven into the cut if one has been made, or 65 into the wood if no cut has been made. The peculiar shape of the nail, narrowing from the point to the head, causes it to draw the parts tightly together and obviates the necessity of using great care to place the pieces 70 *P*, *P'*, with their outer sides exactly meeting at the point *p*, as the nail will when driven in force the parts *P*, *P'*, to meet along the miter-line *P*, *P'*, along which line they may be adjusted after the nail has been driven into the 75 joint.

What I claim as my invention is—

1. A nail for miter joints, consisting of side flanges, and a uniting web, the said uniting web, widening from head to point, and each 80 of the said side flanges tapering from head to point and each being turned up sharply at an angle with the uniting web, whereby they are adapted to cut into the wood to be united, and draw the parts together as the nail is 85 driven, substantially as and for the purpose specified.

2. A nail for miter joints, consisting of two side flanges, and a uniting web, the said side flanges tapering slowly from head to near the 90 point, and then rapidly to the point, the said uniting web, widening slowly from head to point, substantially as and for the purpose specified.

In testimony whereof I sign this specification in the presence of two witnesses.

WILLIAM H. TUTTLE.
